UNITED STATES PATENT OFFICE.

DONALD BARNS MORISON, OF HARTLEPOOL, ENGLAND.

CONDENSING AND COOLING APPARATUS OF THE TUBULAR SURFACE TYPE.

1,184,199.

Specification of Letters Patent.

Patented May 23, 1916.

Application filed May 13, 1915. Serial No. 27,874.

To all whom it may concern:

Be it known that I, DONALD BARNS MORISON, a subject of the King of Great Britain and Ireland, residing at Hartlepool, in the county of Durham, England, have invented improvements in Condensing and Cooling Apparatus of the Tubular Surface Type, of which the following is a specification.

This invention relates to condensing and cooling apparatus of the tubular surface type in which the condensing or cooling liquid flows through the tubes.

The object of the invention is to provide for use in condensers and coolers of the kind referred to, improved apparatus for the purpose of decreasing the resistance offered to the flow of liquid at the entrance into and it may be at the exit from the tubes; and for minimizing the tendency for flocculent material in the liquid to be caught near the entrance to the tubes. According to the invention, some or all of the tubes through which the liquid flows, are each provided at one or both ends with separate funnels.

The accompanying drawings, illustrate apparatus constructed according to the invention and show its application to condensers and coolers of the kind referred to.

Figures 1 and 3 are front views, each showing a part of a tube plate, and Figs. 2 and 4 are sectional side views respectively on lines A—B and C—D in Figs. 1 and 3.

The tubes *a* pass through the tube plate *b* which is provided with cocenter bores *h* and glands *c* in a known manner, and in accordance with my invention I provide each tube with a funnel *d*, the tubular end of which is inserted into the gland *c*, the other end of the funnel being conically flared to such an extent as will bring the flares of the adjacent funnels in abutment or in close proximity with each other. In Figs. 1 and 2 the periphery of the flares are hexagonal and abut against each other, the funnels presenting to the water a surface in one plane, or approximately in one plane, with a conical entry to each tube. In Figs. 3 and 4 the periphery of the flares are circular, but it will be understood that they may be of any convenient shape depending on the disposition of the condenser tubes; the boundary formation of the conical flares being so shaped as to present a surface offering a low resistance to the inflow of water.

The funnels *d* may be formed in any con-

venient manner, as for example they may be stamped out of short pieces of condenser or other tubing, and the tubular ends of the funnels may be slotted at *e* and sprung into the gland ends in order to give them such a firm holding as will maintain the plane surface.

By means of the apparatus described, the resistance to the flow of water into the tubes is decreased, thereby favorably influencing the head and therefore the pumping power; the surface presented to the water being one which will minimize the tendency for flocculent material to be caught near the entrance to the tubes.

What I claim is:—

1. In condensing and cooling apparatus of the tubular surface type in which the joint between each tube and the tube plate is effected by means of a screwed gland, the combination therewith of separate funnels, the tubular ends of said funnels being disposed at the ends of said tubes, for the purpose herein set forth.

2. In condensing and cooling apparatus of the tubular surface type in which the joint between each tube and the tube plate is effected by means of a screwed gland, the combination therewith of separate funnels, the tubular ends of said funnels being inserted into said glands, for the purpose herein set forth.

3. In condensing and cooling apparatus of the tubular surface type in which the joint between each tube and the tube plate is effected by means of a screwed gland, the combination therewith of separate funnels, the tubular ends of said funnels being slotted and sprung into said glands, for the purpose herein set forth.

4. In condensing and cooling apparatus of the tubular surface type in which the joint between each tube and the tube plate is effected by means of a screwed gland, the combination therewith of separate funnels, the tubular ends of said funnels being inserted into said glands, the other ends of said funnels being conically flared so that the flares of the adjacent funnels are in abutment with each other, for the purpose herein set forth.

5. In condensing and cooling apparatus of the tubular surface type in which the joint between each tube and the tube plate is effected by means of a screwed gland, the combination therewith of separate funnels,

the tubular ends of said funnels being inserted into said glands, the other ends of said funnels being conically flared, the periphery of each flare being of hexagonal form and abutting against the periphery of the adjacent flares, for the purpose herein set forth.

6. In condensing and cooling apparatus of the tubular surface type in which the joint between each tube and the tube plate is effected by means of a screwed gland, the combination therewith of separate funnels, the tubular ends of said funnels being

slotted and sprung into said glands, the other ends of said funnels being conically flared, the periphery of each flare being of hexagonal form and abutting against the periphery of the adjacent flares, for the purpose herein set forth.

Signed at London, England, this twenty- ninth day of April 1915.

DONALD BARNS MORISON.
